CLAIM

The ornamental design for a wireless charging case, as shown and described.

DESCRIPTION

FIG. 1 is a front, bottom perspective view of a first embodiment of a wireless charging case, showing my new design;

FIG. 2 is a front view thereof;

FIG. 3 is a back view thereof;

FIG. 4 is a right side view thereof;

FIG. 5 is a left side view thereof;

FIG. 6 is a top plan view thereof;

FIG. 7 is a bottom plan view thereof; and,

FIG. 8 is a left, bottom perspective view of a second embodiment of a wireless charging case.

The broken lines depict portions of the wireless charging case that form no part of the claimed design.
